UNITED STATES PATENT OFFICE.

ELEAZER KEMPSHALL, OF LONDON, ENGLAND

GOLF-BALL.

No. 922,773.

Specification of Letters Patent.

Patented May 25, 1909.

Application filed May 19, 1908. Serial No. 433,673.

To all whom it may concern:

Be it known that I, ELEAZER KEMPSHALL, citizen of the United States, and residing at the Hotel Russell, London, England, have 5 invented certain new and useful Improvements in Golf-Balls, of which the following is a specification.

This invention relates to golf balls, the object being to provide a surface for a golf ball 10 which will not readily become worn, and will thereby avoid the disadvantages of the type of surface usually employed, which after a short time becomes smooth, with the consequence that the club, when striking a ball, is 15 apt to slip relatively thereto.

Another object is to provide a surface which, besides resisting wear and tear, will possess considerable anti-slipping properties.

The invention consists primarily in providing a surface of a golf ball with numerous small circular recesses and central protuberances within the recesses.

The invention also consists in providing a golf ball with projections upon its outer surface, in which recesses are formed.

The invention also consists in providing a golf ball with bands upon its outer surface, said bands comprising alternating wider and narrower portions, the wider portions having 30 recesses.

The accompanying drawings illustrate a ball according to the invention, Figure 1 being an exterior view, while Figs. 2 and 3 are sections on lines 11—11 and 111—111 of 35 Fig. 1, and Fig. 4 is an exterior view of a different embodiment of my invention.

In carrying out the invention as illustrated, the surface of the ball is provided with circular recesses *c*, which are preferably provided 40 with central protuberances *d*. The recesses *c* are preferably formed in a plurality of projections, which, as shown in Figs. 1, 2 and 3, are projecting bands comprising wider portions *a* connected by narrower portions or

necks *b*, and provided with the circular recesses *c*. The protuberances *d* may be of any convenient configuration, but are preferably of dome shape, as indicated in Figs. 2 and 3. Their summits may be flush with the surfaces surrounding the recesses, or may project beyond or below the same. The recess-containing projections may be of complete circular form and need not merge into or be connected with one another, as shown in Fig. 4, where said projections are shown as 55 circular studs *a'*.

Having thus described my invention, what I claim as new and desire to secure by Letters Patent, is:

1. A golf ball having a plurality of circular 60 recesses on its outer surface, and protuberances within said recesses, substantially as and for the purposes hereinbefore set forth.

2. A golf ball having a plurality of projections upon its outer surface, said projections 65 having circular recesses therein, substantially as and for the purposes hereinbefore set forth.

3. A golf ball having a series of projecting bands upon its outer surface, said bands comprising alternating wider and narrower portions, said wider portions having circular recesses therein, substantially as and for the 70 purposes hereinbefore set forth.

4. A golf ball having a series of projecting bands upon its outer surface, said bands comprising alternating wider and narrower portions, said wider portions having circular recesses therein, and protuberances within the 75 said recesses, substantially as and for the 80 purposes set forth.

In testimony whereof I have signed my name to this specification in the presence of two subscribing witnesses.

ELEAZER KEMPSHALL.
